WEATHER GAUGE

Richard I. Misner, Omaha, Nebr.

Application September 21, 1959, Serial No. 57,626

Term of patent 14 years

(Cl. D52—6)

FIG. 1

FIG. 2

FIG. 3

FIG. 4

FIG. 5

Fig. 1 is a side elevational view of a weather gauge showing my new design.

Fig. 2 is a rear view thereof; and

Fig. 3 is a top plan view thereof.

Figure 4 is a front perspective view of the weather gauge of my design; and

Figure 5 is a vertical cross-sectional view taken through the triangular area at the right of the gauge in Figure 4, parts broken away for convenience of illustration.

The undisclosed side of the weather gauge is substantially the same in appearance as the side shown.

I claim:

The ornamental design for a weather gauge, as shown and described.
